Primary Examiner — Paula Allen Greene

(57) **CLAIM**

The ornamental design for a gaming headphone, as shown and described.

DESCRIPTION

FIG. 1 is a perspective view of a gaming headphone showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of the gaming headphone taken from the circle portion in FIG. 3.
The broken lines depict environment only and form no part of the claimed design.**1 Claim, 8 Drawing Sheets**(56)
